FLEXIBLE DRINKING STRAW

William Nardone, Revere, Mass., assignor to Sweetheart Plastics, Inc., Wilmington, Mass., a corporation of Maryland

Filed Oct. 22, 1965, Ser. No. 87,734

Term of patent 14 years

(Cl. D94—3)

FIG. 1 is a side view of the flexible drinking straw; and

FIGS. 2, 3 and 4 are cross-sectional views taken on section lines 2—2, 3—3 and 4—4, respectively, of FIG. 1.

The characteristic feature of the novel design resides in the specific configuration of the folded portion of the straw as shown.

I claim:

The ornamental design for a flexible drinking straw, as shown and described.
